CORRUGATED FASTENER DRIVING
MACHINE

Albert E. Cranston, Wenatchee, Wash.

Application March 13, 1935, Serial No. 10,835

5 Claims.

(Cl. 1—9)

This invention relates to fastener applying machines and it has reference more particularly to machines for joining together board pieces by means of fasteners of a kind known in trade as "corrugated fasteners"; it being the principal object of this invention to provide a machine whereby the fasteners are cut to a desired length from a supply strip and are driven into the matched edges of the parts to be joined in an accurate, 5 and permanent manner and with rapidity.

More specifically stated, the objects of the present invention reside in the provision of a fastener driving machine of the kind above stated, wherein reciprocating feed devices operate to intermittently advance a supply strip of corrugated material into the machine and wherein a reciprocating block, mounting a cutter, operates in timing with the action of the feed devices to cut off definite lengths of the strip to form the fasteners and to 10 position these fasteners in the path of travel of a reciprocating hammer whereby they may be driven into the adjacent or matched edges of board pieces, properly located on a supporting table, thereby to permanently and securely join them.

25 It is also an object of the invention to provide novel means for feeding the corrugated strip of fastener material and a guide means for the strip which prevents its buckling under the forwarding action of the feed devices.

30 Another object of the invention resides in the use of magnetic means for supporting the fasteners during their transfer from the "cut off" position to the driving position.

Still another object resides in the provision of 35 means which operates automatically in timing with the operation of the hammer, to clamp the board pieces against movement during the fastener driving operation.

In accomplishing these and other objects of 40 the invention, I have provided the improved details of construction the preferred forms of which are illustrated in the accompanying drawings, wherein—

Fig. 1 is a perspective view of a fastener forming and driving machine embodied by the present invention.

Fig. 2 is a detail of the driving clutch mechanism of the machine in release position.

Fig. 3 is a similar view with the clutch mechanism in position set for driving.

Fig. 4 is a detail, in plan view, of the co-acting fastener cutters.

Fig. 5 is an enlarged side view of the fastener driving head.

55 Fig. 6 is a horizontal section, taken on line 6—6

in Fig. 5, particularly illustrating the strip guides, the strip feed mechanism and the reciprocating cutter block.

Fig. 6a is a cross sectional detail of the strip feed block, as seen on line 6a—6a in Fig. 6.

Fig. 7 is a cross sectional detail of one of the feed pawls, as on line 7—7 in Fig. 6.

Figs. 8, 9, 10 and 11 are views showing successive positions of the feed slide actuating cam and lever.

10 Fig. 12 is a sectional detail, particularly illustrating the fastener cut off block, its actuating lever, the fastener driving hammer and the two cams for actuating the cut-off block and hammer respectively; both the block and hammer being shown in retracted positions.

Fig. 13 is a view of the same parts with the block advanced and the hammer advanced to the limit of its driving position.

Fig. 14 is a development of the strip feeding cam.

Fig. 15 is a development of the cam which actuates the strip cut off block.

Fig. 16 is a development of the hammer actuating cam.

Fig. 17 shows in side elevation the table adjusting means.

Fig. 18 is a side elevation of the board clamp mechanism.

Fig. 19 is a horizontal section on the line 19—19 in Fig. 5 and Fig. 13.

Referring more in detail to the drawings—

In its present preferred form of construction the machine comprises a tubular, supporting standard, or post 1, equipped at its lower end with a plurality of radially directed supporting legs, or brackets 2, whereby the standard will be retained solidly in upright position. Fixed on the upper end of the standard is a horizontal, tubular bearing portion 3 axially containing the main drive shaft 4 which is revolvably supported in suitable bearings, as designated at 5—5. Keyed on the shaft 4 at one end is a cam wheel 6 and adjacent thereto, but freely revolute on the shaft, is a belt pulley 7, about which a belt 8 operates to drive the machine; the driving of shaft 4 being under control of a clutch mechanism located between wheels 6 and 7, as presently will be described.

Permanently secured to the standard 1, at a distance somewhat spaced below the bearing portion 3, is a horizontal abutment plate 10 upon which the strip feeding devices and the strip cutting means, presently described, are mounted, as shown in Fig. 6. This plate 10 is braced and

supported along one longitudinal edge to give it added rigidity by a web 11 depending from the tubular portion 3, and it is further braced at its outer end through the mediacy of a flat connecting plate 12 that is fixed at its lower end to the outer end of the plate 10 by bolts 13, as seen in Fig. 5, and at its upper end is secured to the outer end of the bearing portion 3.

At the rearward side of the standard 1 is a suitable support 14 by which a roll of corrugated metal strip, as designated at 15 in Fig. 1, may be placed for supplying the machine. The strip 15 is drawn off from the roll and is threaded into the machine as is best shown in Figs. 5 and 6; the strip being disposed vertically with its blunt edge at the top and its sharpened edge pointed downwardly. In threading the strip into the machine it is passed closely about the standard 1, as shown in Fig. 6, then extended between a flat upright guide plate 16 which extends lengthwise of plate 10, and a stiff wire 17. The plate 16 and wire together form a guide channel between them for the strip of material and they prevent the strip buckling under the feeding action.

By reference to Fig. 6, it will be observed that the guide plate 16 is backed by a rib or flange 18 that extends lengthwise of the plate 10 and that its outer end terminates in exact alinement with the surface of a block 20 that is fixed solidly to plate 10. It will also be observed that the wire 17 is spaced from the plate 16 the thickness of the corrugated strip and engages the strip lengthwise thereof and about mid-way of its top and lower edge, as shown in Figs. 6a and 7. One end of the wire is supported in a block 22 that is fixed to plate 10 in spaced relation from block 20 to provide a passage for the corrugated strip, and the other end is seated in an encircling groove 23' of a wheel 23 that is mounted on the plate 10 near the standard 1.

When the corrugated strip 15 is threaded into the machine up to the "cut-off" position, as seen in Fig. 6, it is then disposed between the spaced, adjacent surfaces of the blocks 20 and 22, and it is held at this end against any possible backward movement by means of two pawls 24—24 which are located within a recess 22' of the block 22 with their outer ends urged yieldingly into holding contact with the corrugations of the strip. Each pawl is keyed on a vertical supporting pin 25 revoluble in the block, as seen in Fig. 7, and a coiled spring 26 is fastened at one end to the block and at its other end to an arm 27 on the pin and operates to urge the pawl into holding contact with the strip, but yields to allow the pawl to ride over the corrugations on advancement of the strip.

Reciprocally mounted on the plate 10 is a strip feeding block 30. This is guided in its reciprocal movement by a shaft 31 that has one end fixed in the block and its other end reciprocally operable in a bore 32 in the block 22.

The block 30 reciprocates parallel with the direction of the strip 15, and it has a recess 30a at one side in which a pair of feed pawls 35—35 are contained to engage the corrugations of the strip to effect its advancement with each forward, reciprocal action of the block 30. The pawls, in this instance, are mounted on supporting pivot pins 36 in the same manner as are the pawls 24 and are likewise yieldingly urged into feeding contact with the strip corrugations.

The block 30 reciprocates once with each revolution on the shaft 4 and its movement for feed-

ing the strip into the machine is effected by the cam wheel 6 through the mediacy of a rocker lever 38 and a connecting link 39.

By reference to Fig. 5, it will be observed that the lever 38 is pivotally supported at a point between its ends on a pivot 40 secured in a bracket 40' fixed to the upper end portion of standard 1. At the upper end of the lever is a cam follower roller 41 in rolling contact with the cam surface of wheel 6. At its lower end, the lever is connected pivotally to the link 39 by a pivot bolt 38a, and the link has a laterally turned end 39a by which it is connected operatively to the block 30. A coiled spring 43 is connected under tension to the lower end of the lever 38 and to a clip 44 on the block 22, as seen in Figs. 5 and 6. Thus, the action of the lever, under influence of the cam 6, is to shift the block 30 outwardly, preparatory to a feeding action of the strip, and the spring 43 then operates to feed the strip forwardly; it being understood that with the forwarding movement of the block by the action of the spring, the pawls 35—35 engage the strip and advance it.

The action of lever 38, under influence of the cam 6 is best illustrated in Figs. 8 to 11 inclusive, and the development of the cam is shown in Fig. 14 from which it is understood that there is a rather quick, inward feeding of the strip as designated by the interval within the bracket "f".

It is to be observed by reference to Fig. 7 that the swinging ends of the several pawls are bifurcated to receive the wire 17 between their end portions. Also, the edges of the reciprocating block 30 are recessed to seat the wire therein, as seen in Fig. 6a.

Mounted upon the outer end portion of plate 10 is the strip "cut-off" block 48. This block is reciprocally contained between guides 45 and 46 for movement in a direction transverse to the direction of feeding of the strip 15, and it is provided with an elongated recess 49 opening to one side edge to register with the strip guiding channel between blocks 20 and 22 when the strip cut-off block is retracted to one extreme of its movement, thereby providing that the end of the strip 15 may be advanced into the recess, as it is shown in Fig. 6. Set within and secured to the block 48 adjacent one side of the recess and at the mouth thereof, is a cutter block 50 having a shearing edge 51. This cutter block is arranged to co-act with a similar, opposingly mounted cutter 52 set in the block 20 so that movement of the block 48 from the position of Fig. 6 to its other extreme will cause the cutters to shear off that part of the supply strip that is contained in the recess 49, thus to form a fastener of definite length. The reciprocal action of the cut-off block 48 is timed with the feeding of the strip so that it takes place immediately following the advancement of the strip end into the recess 49 under the action of cam 6.

The means for controlling reciprocal action of the block 48 comprises a cam 55 that is fixed to the outer end of shaft 4 and rotates therewith. This cam oscillates a lever 56 that is pivoted at a point intermediate its ends, on a pivot 57 which is supported by a bracket 58 from the front end plate 12, as seen in Fig. 19. The lower end of the lever 56 is extended into a socket or recess 59 in the block 48, and its upper end carries a follower roller 60 in contact with the cam. The design of the cam and its relation to the setting of cam 6, is such that the block 48 will be shifted laterally immediately following the feeding of the

strip into the recess 49, thus to sever a fastener from the strip. The development of this cam, as seen in Fig. 15, discloses a rise at "g" which is the interval of shifting of the block, and it also shows a relatively long interval of rest following the shifting; this being the interval during which the driving of the fastener takes place and which requires that the block 48 remain stationary in view of the fact that the hammer, in driving, is 10 extended into the slot 48, as will hereinafter be explained.

Return of the cut-off block 48 to retracted position, as in Figs. 6 and 12, is effected by a spring 62 that is coiled under tension about the supporting pivot 57 of lever 56, with one end attached in bracket 58 and its opposite end attached to the lever, as will be understood by reference to Figs. 12 and 19.

Before describing the hammer and its operating means, it will be explained that board pieces, when they are to be fastened together, are located edge to edge upon a horizontal, supporting table 65 that is spaced below the plate 10 and which table is adjustably supported from the standard 1 to accommodate boards of different thickness, as later described. When the boards, *a* and *b*, are placed upon this table, as shown in Figs. 5 and 6, the matched edges to be joined are located directly beneath and transversely of the recess 49 of block 48 so that when a fastener is driven from the recess by the action of the hammer, substantially equal lengths thereof will be embedded in the two board pieces, as is the fastener 15x, shown in Fig. 6. It is understood, of course, that the recess 49 extends clear through the block 48 and that the under side of the block is uncovered by the plate 10.

The hammer employed for driving the fasteners comprises a vertically reciprocable bar 70 contained in a guide housing 71 that is fixed to the plate 12, as observed in Figs. 1, 12, 13 and 20. At its lower end, the bar 70 has a fastener driving plate 72 for passing through the recess 49 and for engaging the top edge of the fastener on downward travel of the hammer. At the upper end of the hammer is a roller 73 acted on by a driving cam 74 fixed to the outer end of and rotating with shaft 4. The cam 74 is designed to drive the hammer downwardly from the position of Fig. 12, to that of Fig. 13 during that period of rest of the block 48 following its movement to its advanced position of Fig. 13. A development of the cam 74 is seen in Fig. 16 wherein the interval at "d" designates the driving period and 55 the interval at "e" the up stroke of the hammer.

It will be explained here that the several cam developments of Figs. 14, 15, and 16 are illustrated in their proper relationship from which it is evident that the driving and the lifting of the hammer takes place during the period of advancement of the block 48 and during retractive movement of the strip feed block 30. Retractive movement, or lifting, of the hammer after a driving operation is effected by a lift lever 78 which, as seen in Fig. 5, is pivoted on a stud 79 fixed in the web 11. One end of the lever 78 engages with the under side of a lug 80 on the lower end portion of the hammer bar 70 while the other end is urged downwardly by a coiled spring 81 which is mounted, under compression, in a housing 82 attached to the under side of the bearing portion 3. Thus, the spring 81 operates to lift the hammer under control of movement of the cam 74.

As a feature of the present invention, an elec-

tro-magnet 85 is located in the block 48, as seen in Fig. 6 and this operates by magnetic attraction to hold the severed fasteners in recess 49 during the shifting of the block and until they are driven. As illustrated in Figs. 5 and 6, circuit wires 86 and 87 lead to the magnet through a transformer 88.

In the present machine, a manually actuated clutch is arranged to provide for one cycle of operation, then to automatically stop the machine. This clutch mechanism is shown best in Figs. 1 to 5, inclusive. By reference to Figs. 2 and 3, it will be observed that there is a heavy stud 90 extending from near the hub of the belt wheel 7 toward the cam wheel 6, and there is a lever 92 pivotally supported by a stud 93 extending from the inside of the cam wheel 6. This lever is adapted to swing between the extreme positions in which it is shown, respectively, in Figs. 2 and 3. At its inner end the lever 92 carries a stud 94 and there is a coiled spring 95 mounted by a support 96 fixed in the cam wheel and this spring acts against the outer end of the lever 92 to yieldingly urge its inner end to a position at which the stud 90 of the revolving belt wheel will come into driving abutment with the stud 94, as seen in Fig. 3. Fixed upright on the housing 3 is a bracket 98 and supported pivotally thereon by a bolt 99 is cam lever 100 which lies in the plane of travel of the lever 92. At its outer end the lever 100 is connected by a downwardly extended link 101 with a lever arm 102 fixed on a horizontal shaft 103 to which a foot pedal 104 also is fixed. The shaft 103 is revolvable in a support 105 attached to the lower end of standard 1. Also, a coiled spring 106 is attached at its opposite ends, under tension, to the link 101 and to the standard 1, as seen in Fig. 17, and this yieldingly holds the clutch trip lever 100 in clutch release position, as shown in Fig. 2, and at which position its swinging end is in the path of travel of the outer end of lever 92. Therefore, normally the lever 92 is held by lever 100 in "release" position, as shown in Fig. 2, and there is no driving contact between the studs 90 and 94. However, when the foot pedal is momentarily depressed, and the lever 100 lifted clear of lever 92, the spring 95 then effects a movement of lever 92 whereby a driving connection between the belt wheel and cam wheel 6 is made, and rotation of shaft 4 is the result. This rotation of shaft 4 will continue as long as the clutch release lever 100 is held in the clear of lever 92.

Adjustment of the base or table 65 relative to the driving head to accommodate boards of different thickness, is made by means best shown in Fig. 17 wherein it is shown that table 65 is supported from a split sleeve 112 slidable lengthwise on standard 1. A rack 113 is fixed lengthwise of the standard and a pinion gear 114, meshing with the rack is keyed on a crank shaft 115 extended between spaced flanges 116-116 of the sleeve. By rotation of the crank, the pinion gear will be caused to travel up or down the rack to raise or lower the table accordingly. Any adjustment made may be retained by clamping the pinion against turning between the plates 116-116 through the mediation of bolts 118 extended between the plates.

In order that the boards being joined may be held against movement during a driving operation, a clamp lever arm 120 is pivotally mounted on the end of the bolt 79 opposite the lever 78. The lever 120 has one end extended to a position

- overlying the adjacent edges of boards to be joined, as seen in Fig. 18, and it has its opposite end connected with a coiled spring 121 which is attached to the frame and which operates to 5 yieldingly urge the outer end of the lever into clamping contact with the boards. A link 125 connects lever 120 with lever 78 so that as the lever 78 is actuated downwardly, the clamp lever is simultaneously actuated to clamping position, 10 and when the hammer is raised, the clamp is likewise raised.

Having thus described my invention what I claim as new therein and desire to secure by Letters Patent is—

- 15 1. In a corrugated fastener driver, a driver member, advancing means for a strip of fastener material, a transfer block having a slot therethrough, and movable from a position at which said slot will receive the end portion of said strip 20 material therein to a position in registration with the driver for driving the fastener, a shear block coacting with the transfer block for severing said end portion from the strip and a magnetic element associated with the block for magnetically 25 retaining the fastener in the slot prior to driving.

2. In a corrugated fastener driver, the combination with a reciprocating hammer, and means for advancing a strip of fastener material, of a 30 reciprocally movable cut-off block having a slot for reception of an end portion of the strip of fastener material as it is advanced, a cut-off member, against which the advanced end portion of the strip in said slot is sheared off incident to movement of the block to a position for placing the detached piece under the hammer, and a magnetic element associated with the block for magnetically supporting the fastener in the seat prior to its being driven.

- 35 3. In a corrugated fastener driving machine, the combination with a fastener driver, a cut-off member timed therewith, and means for supporting a supply strip of corrugated fastener material, of a feed mechanism for the strip, com-

prising a reciprocally moving block, pawls mounted by the block to engage the strip to advance it with advance movements of the block, yieldable means engaging the strip to preclude retraction thereof, a cam revolving in timing with 5 the actions of the cut-off member, a lever positively actuated by the cam to retract the first mentioned block after advancement of the strip; and a spring, under tension, for moving the block to advance the strip under control of the 10 cam.

4. In a corrugated fastener driving machine, a rotatably driven shaft, a hammer reciprocally actuated in timing with rotations of the shaft, a cut-off block reciprocally actuated in timing with 15 rotations of the shaft, and means for feeding a strip of fastener material to the cut-off block; said means comprising a guideway for the strip, a stationary block adjacent thereto, pawls on said block engaging the strip to prevent retraction thereof, another block adjacent the guideway to reciprocate parallel thereto, pawls in said block for engaging and advancing the strip, a cam on said driven shaft, a pivotally mounted lever engaging the cam and connected with the 20 reciprocating block to retract it after advancement of the strip, and a spring attached under tension to the block to advance the strip under control of the cam.

5. In a corrugated fastener driving machine, 30 in combination, a cut-off member, and a feed mechanism for advancing a strip of corrugated material, intermittently to the cut-off member; said feed mechanism including a guideway in which the strip is enclosed, formed by stationary 35 plates at one side, and at top and bottom edges, a block reciprocally movable at the other side of the guideway parallel thereto, with pawls engaging the strip to advance it, and a stiff wire disposed lengthwise of and supported to engage 40 the strip at that side to prevent outward buckling thereof.

ALBERT E. CRANSTON.
